ATTORNEY: 75-

Patented Oct. 14, 1924.

UNITED STATES PATENT OFFICE.

LESTER B. CHISHOLM, OF MELROSE, MASSACHUSETTS

BELTING.

Application filed November 20, 1920. Serial No. 425,514.

To all whom it may concern:

Be it known that I, LESTER B. CHISHOLM, of Melrose, in the county of Middlesex and State of Massachusetts, have invented a new and useful improvement in Belting, of which the following is a full, clear, and exact description, reference being had to the accompanying drawings, forming a part of this specification, in explaining its nature.

10 The invention relates to belting for the transmission of power and essentially that made of fabric material for use on flat-faced pulleys.

The object of the invention is to provide a better running belting than that heretofore employed and to provide means whereby the life of the belting will be prolonged.

These objects are attained by providing a belting having the inherent capability of making its sides hug the pulley around which the belting is passed. This tends to keep the belting centered upon the pulley and minimizes slippage between the belting and the pulley. It also prevents wear or fraying of the belting along its side edges, which is a common difficulty with the present type of belting and arises by the rubbing of the belting against the flanges of the pulley or supports carrying the pulley.

30 The manner in which the belting is made to have the inherent capability of making its sides hug the pulley as aforesaid can best be seen by reference to the drawings in which is shown a piece of belting illustrative of the invention and comprising a woven structure.

Figure 1 is a plan of the belting.

Fig. 2 is a cross section thereof.

Fig. 3 is a diagrammatic plan of certain unravelled portions of the belting shown for the purpose of illustrating certain capabilities residing in it as will later be explained.

Fig. 4 is a cross section of the belting in enlarged detail.

Referring to the drawings:

1 represents a piece of the belting of which 2 represents the under or working face of the belting, 3 the upper face or back of the belting and 4, 4 the respective sides thereof.

By reference to Fig. 2 it will be seen that the belting has normally a certain bend or angularity in cross section which tends to throw the sides 4, 4 in the general direction of the under face of the belting. Such

angularity is initially attained by forming within the belting on the upper face or back thereof a raised cord or rib 5 extending longitudinally.

In Fig. 4 where the woven structure of the belting is shown in enlarged detail, 6 represents warp on the back and 7 back pick. 8 represents warp and 9 pick on the under face. 10 and 11 represent, respectively, warp and pick at either edge. 12 is stuffing warp and 13 binder warp.

As thus indicated the rib 5 is produced by the addition to the woven structure of more ends of back warp 6 at the particular point where the cord or rib is desired than elsewhere. There are also several ends of stuffing warp 12 placed within the body of the belting beneath the rib which assist in giving character to the rib. The stuffing warp beneath the rib and also that along the sides of the belting assist also in giving strength and body to the entire structure. When the belting is woven the back pick 7 weaves through the extra ends forming the rib on the back, while the pick 9 weaves through the plain fabric on the face of the belting. The effect is that the belting thus formed is made to have a certain angularity or body flexure, when viewed in cross section as shown in Fig. 2 or such bend that the sides of the belting are turned in the general direction of its under face and will accordingly initially contact with the pulley around which the belting is running and under tension will be made to flatten out and hug the pulley.

One reason why the belting has inherent transverse body flexure, and hence hugs the pulley at and near its edges, is that the under face picks 9 are shorter than the back picks 7 inasmuch as the back picks must weave through the raised cord or rib on the back of the belting; consequently the shorter picks will tend to exert a pull on the sides of the belting.

It is also to be observed by reference to Fig. 3, which shows diagrammatically an unraveled portion of the pick, that the weaving of the back pick 7 through the raised cord or rib on the back tends to effect a bend in the thread, while the under face pick 9 remains substantially unbent. The bends thus formed in the back picks collectively assist in imparting an angularity to the belting and throw the sides thereof in the general direction of its under face

in accordance with the purpose of the invention as before outlined.

In practice the belting is customarily made with from 50 to 60 picks to the inch reckoning each face and back pick as one pick each. This gives desirable strength and body to the belting.

In the claims I use the term "transverse flexure" to define a flexure visible in transverse section as illustrated in Figs. 2 and 4.

Having thus fully described my invention, I claim and desire to secure by Letters Patent of the United States:—

1. As an article of manufacture, machine belting of woven material having inherent transverse angular body flexure induced by the weave structure.

2. As an article of manufacture, machine belting of woven material characterized by inherent transverse angular body flexure induced by the presence of a rib extending along the back of said belting and formed in the weave structure thereof.

3. As an article of manufacture, machine belting of multiple ply interwoven fabric material characterized by inherent transverse angular body flexure induced by the presence, in a ply thereof, of a rib extending longitudinally of the belting and formed by the weave structure.

4. As an article of manufacture, machine belting of multiple ply interwoven fabric material characterized by inherent transverse angular body flexure induced by the bunching together of a number of warp threads to form a rib extending longitudinally, said bunched warp threads being bound by weft threads interwoven therewith.

5. As an article of manufacture, machine belting of two-ply interwoven fabric material characterized by inherent transverse body flexure induced partially by the presence in a portion of one ply or a greater number of warp threads than in the adjacent corresponding portion of the other ply and partially by the presence between said adjacent portions of the plies of a number of closely spaced stuffing warp threads.

6. As an article of manufacture, machine belting of two-ply interwoven fabric material, characterized by inherent transverse body flexure induced by an area of augmented warp in one ply accentuated by stuffing warps between the two plies adjacent said augmented warp, said augmented warp being tightly interwoven with weft threads to form a rib extending longitudinally of the belting, and said stuffing warps being confined by binding threads connecting the plies.

7. As an article of manufacture, machine belting of two-ply interwoven fabric material characterized by inherent transverse body flexure induced by the presence in a portion of one ply of a greater number of warp threads than in the adjacent corresponding portion of the other ply, the warp threads in the ply of less number being closely spaced.

8. As an article of manufacture, machine belting comprising a multiple ply interwoven fabric, characterized by inherent transverse body flexure induced by differences in the weave structure of respective plies.

9. As an article of manufacture, machine belting of woven material having inherent transverse body flexure, the concave surface of said belting being substantially smooth and the convex surface being woven with a longitudinal rib.

LESTER B. CHISHOLM.
